TRAMWAY STATION CONSTRUCTION

Joseph B. Strauss, Chicago, Ill.

Application August 6, 1931, Serial No. 555,641

2 Claims. (Cl. 104—94)

This invention relates to tram-way station constructions and has for its object to provide a new and improved device of this description. The invention has as a further object to provide a tram-way station which shall be particularly adapted for a single arch construction and which shall be contained within the limits of that arch. The invention has as a further object to provide a tram-way station which shall be convenient for the passengers and which the passengers may easily, quickly and safely enter and depart from. The invention has other objects which are more particularly pointed out in the accompanying description.

Referring now to the drawing, Fig. 1 is a view showing one form of station embodying the invention, some of the parts being shown in section;

Fig. 2 is a view showing an elevation of the station illustrated in Fig. 1;

Fig. 3 is a view taken on line 3—3 of Fig. 2;

Fig. 4 is a plan view of one half of the station illustrated in Fig. 2 on line 4—4 of Fig. 2 with the pier in section.

Fig. 5 is a diagrammatic view showing the cars in loading position with relation to the loading platform.

Like numerals refer to like parts throughout the several figures.

In the construction shown I have illustrated what may be termed the boulevard type of tramway, which consists of a series of single arches 1 extending between posts 2. In the construction shown the posts and arches are located in the center of the street, there being pavements 3 and 4 on each side thereof and sidewalks 5 and 6. At the sidewalk line are provided the kiosks 7 and 8 through which the passengers enter, the passengers passing along the stairways 9 and 10 leading to the tunnel 11 under the street. This tunnel is preferably located intermediate the two posts 2^a and 2^b and there are stairs 12 which lead therefrom up to the sidewalks 13 in proximity to the posts 2^a and 2^b. Connected with the arch portion are cross members 13^a upon which are rails 14^a and 15^a along which run the trucks 14^b and 15^b to which are connected the cars 14 and 15, the cars being on opposite sides of the arch portion.

In the construction shown, see Fig. 2, the two adjacent arches 2^a and 2^b are provided with passageways 16 and 17, which are on the street level and which are provided with stairways along which the passengers travel, such passengers passing from the sidewalks 13, 13 up through said

passageways to the station platform. The station platform 18 is suspended under the arch and will be central between the tracks, and passengers will enter and depart from the cars from this central platform, the cars being located on each side thereof.

The roof of the station will be built into the arch and will curve downward at the sides. Verticals 19 connect the platform with the arch so as to support the platform. The platform 18 is connected by the inclines 20 and 21 with the passageways 16 and 17. These inclines are preferably arranged with steps. Along the inclined passageways and the platform is a railing 22 and above the railing on the platform are the glass panels 23 extending to the roof 24.

Each station will have two doors at each side automatically operated so that they cannot be opened until the car is exactly opposite them, nor can the train start until the doors are closed.

It will be seen that in this construction the passengers will reach the station directly from the street level by passing through the passageways 16 and 17 and along the inclines 21 and 20.

In this construction there is provided a series of main girders comprising a central longitudinal member supported on posts, and there are a series of transverse members carried by the central member and tracks supported on said transverse members, with cars operating on these tracks and below the transverse members on either side of the central longitudinal member and parallel to it. There is a loading platform contained within the limits of the central member and two of the posts which support it. The cars have means of access to said loading platform and there is means of access to said loading platform from the ground, the cars when being loaded and the means of access to said loading platform from the ground, being between the adjacent supporting posts.

It will further be noted that the supporting structure for the cars extends along the center of the street and has a relatively narrow central load supporting member with a loading station contained within the limits of this supporting structure, and with a passageway extending transversely across the street and beneath the surface thereof, with means of access to said passageway from the sidewalk and from the street surface under the station, so that passengers may enter and leave the station without crossing through traffic.

It will further be noted that the loading platform is enclosed and is provided with doors so

arranged as to be opposed to the doors of the cars so that several cars can be loaded simultaneously. This construction is shown diagrammatically in Fig. 5, wherein is shown a loading platform 18, the metal of which is preferably at the center line of the structure. This loading platform has the enclosing device 19^a and there are provided the doors 20^a, 21^a and 22^a, arranged so that with a three car train the door 22^a can be 5 opposite the end door 23^a of the first car, and the door 21^a opposite the middle door 24^a of the middle car, and the door 20^a opposite the end door 25^a of the third car.

I claim:

- 15 1. A tramway station construction for tram cars comprising an arch portion, supports for the arch portion comprising parts arranged at intervals, cross members connected with said arched portion which form a support for the tram cars, the tram cars being connected with said cross members on opposite sides of said arched portion,
- 20

a platform connected with and suspended beneath said arch portion between said cars, one of said parts having a passageway extending therethrough for the passengers, and a passenger connection between the passageway and said platform. 5

2. In a suspended railway system comprising a central longitudinal member, transverse members, posts spaced apart for supporting said central longitudinal member and transverse members, and tracks supported on said transverse members, cars operating on said tracks and below said transverse members on either side of the center longitudinal member and parallel to it, and a loading platform located centrally under 15 said central member and between said central member and the opposed walls of the two adjacent posts thereof, and means of access to said loading platform from the ground.
